UNITED STATES PATENT OFFICE.

EDWARD WALKER, OF NEW YORK, N. Y.

TAILOR'S PRESSING-MACHINE.

SPECIFICATION forming part of Letters Patent No. 300,817, dated June 24, 1884.

Application filed March 16, 1883. (No model.)

To all whom it may concern:

Be it known that I, EDWARD WALKER, of the city, county, and State of New York, have invented a new and Improved Tailor's Pressing-Machine; of which the following is a full, clear, and exact description.

The object of my invention is to provide a new and improved machine for tailors' use in pressing and ironing articles of clothing.

10 The invention consists in a pressing or ironing machine constructed with an ironing-board mounted on a carriage adapted to run on a table, above which ironing-board a smoothing-iron is pivoted in a frame suspended from a weighted lever, which is connected with or can be operated by a foot-lever underneath the table, the above-mentioned carriage having chains attached to the ends and wound in opposite directions on a drum mounted in a 15 shaft provided with a crank-handle. The double smoothing-iron consists of two smoothing-irons provided with side bars, and having trunnions, one of which trunnions is provided with a slot, through which a gas-pipe passes 20 for heating the smoothing-iron, and the other trunnion is provided with a crank-handle for revolving the smoothing-iron and adjusting it in the desired position.

25 Reference is to be had to the accompanying drawings, forming a part of this specification, in which similar letters of reference indicate corresponding parts in all the figures.

Figure 1 is a front elevation of my improved tailor's pressing-machine, the foot-lever being shown in section. Fig. 2 is a cross-sectional elevation of the same on the line *xx*, Fig. 1. Fig. 3 is a longitudinal sectional elevation of the ironing-table. Fig. 4 is an end elevation of my improved revolving double 30 pressing-iron.

A table, A, is provided at the ends with folding wings B, having folding legs C, so that the table will not occupy much space when not in use. The table A is provided with two 35 longitudinal tracks, *a*, which also run over the wings on which tracks wheels *b* of a platform or carriage, D, run, which platform is provided at one end with a fixed standard; and at the opposite end with a standard, E', 40 held to slide in the direction of the length of the platform between two longitudinal guide-

strips, *d*, secured on the upper surface of the platform.

To the fixed standard E a narrow ironing-board, F, is pivoted, which is provided on its under surface with a longitudinal ridge, *g*, which fits into a recess in the upper end of the movable standard E'. The ironing-board should be covered with fabric, flannel, &c., in the usual manner.

To each end of the car or movable platform D a chain, G, is attached, which chains are wound in opposite directions around a drum, H, mounted on a transverse shaft, J, journaled below the table A, and provided at the front 65 of the table with a crank-handle, K, whereby, by turning the crank-handle K in one direction or the other, the car or platform D can be moved in the direction of its length in one direction or the other, as may be desired. A 70 horizontal frame, L, projecting over the top of the table, is attached to the upper end of a standard, L', secured to the rear of the table, which frame L is provided in the outer ends of its side bars with recesses for receiving the 75 hollow trunnions M, projecting from side bars N, connecting two smoothing-iron, O, the smoothing-faces of which project in opposite directions. The double smoothing-iron thus formed is journaled in a U-shaped hanger or 80 frame P, suspended from the end of a lever, Q, pivoted on a standard, Q', on the frame L. The outer end—that is, the end toward the front of the machine—of the lever Q is provided with a weight, R, and to the inner end 85 of the said lever Q a cord or chain, S, is attached, which passes over pulleys *h* and *l* on the frame of the table, and is attached to a foot-lever, T, the end of which projects from the front of the table. One trunnion, M, is 90 provided in its end with a slot, W, parallel to the bars N, and through the said slot a gas-pipe, U, projects into the recess or hollow formed by the side bars, N, and the smoothing-irons O. One or more burners are secured on 95 that part of the pipe U within the smoothing-iron, and a piece of wire-gauze, V, is held above the burners to insure a thorough combustion of the gas and to prevent the smoothing-iron from being soiled by smoke or soot. 100 The other trunnion of the double smoothing-iron is provided with a crank-handle, X. The

double smoothing-iron can be turned on the transverse central axis, which passes through the middle of the trunnions by means of the crank-handle Y, so that one smoothing-iron 5 can be heated while the other is being used—that is, while the smoothing-surface of one smoothing-iron faces downward the opposite surface of the other smoothing-iron is being heated by the flames of the burners in the pipe U. The slot W permits of raising the smoothing-iron without striking against the pipe U.

The operation is as follows: The ironing-board F is raised from the standard E', and 15 the article to be ironed is placed on the same, or the board is passed into the said article. For instance, the board can be passed into the sleeve of a coat, &c., and the board is then placed back on the standard E'. The free end 20 of the ironing-board can project a greater or less distance from the free end of the standard E', according to the manner in which the standard E' is adjusted—that is, according as it is adjusted a greater or less distance from the 25 free end of the standard E'. By this means a coat-sleeve may be ironed on the end of the board projecting beyond standard E, leaving the garment to be turned and handled more freely. Ordinarily the smoothing-iron is held 30 raised by passing the foot-lever T into a notch, m, in one of the standards of the table; but after the ironing-board on which the article to be pressed is held has been passed under the smoothing-iron, the outer end of the bar T is 35 removed from the notch m, thereby permitting the weight R to press the frame P downward, the weight R acting on the frame and pressing the smoothing-iron on the article. The ironing-board is then moved forward and 40 back under the smoothing-iron, which rests on it, by turning the crank-handle K alternately in opposite directions until the article has been pressed, ironed, and smoothed sufficiently. Then the smoothing-iron is raised and is 45 turned so that the other iron, O, will be heated, and another article can be placed on the ironing-board.

Seams, &c., must be ironed or pressed under 50 very great pressure, and at present considerable time and labor are spent by tailors in pressing and smoothing seams. By means of my improved smoothing-iron any seams, &c., can be pressed and smoothed in a few moments and no time is lost in heating the irons, as one iron 55 is being heated while the other is being used.

Gasoline or some other burning fluid may be used in place of gas to heat the smoothing-iron.

Having thus described my invention, I claim as new and desire to secure by Letters Patent—

1. A stationary table having horizontal 60 guideways, an ironing-table provided with devices to engage said ways, and means for reciprocating said table thereon, a stand fixed upon said stationary table provided with horizontal arms having vertical guides, a smoothing-iron located between said guides, and a post 65 fixed to the reciprocating table at one end and a groove along a portion of the other end, in combination with a press-board loosely pivoted on the fixed post, provided with a rib on 70 its under side, and a post adjustable in said groove having a slot in its top shaped to receive the rib of the press-board, as described.

2. The combination, with a stationary table, 75 an ironing-table mounted to reciprocate thereon, and a post provided with vertical guideways fixed to said table, of a two-faced hollow smoothing-iron having trunnions engaging said guideways, means for reciprocating said iron in said ways, a vertical slot or aperture 80 through one of said trunnions to the hollow interior of said smoothing-iron, and a fixed pipe entering said iron through said aperture, substantially as described, whereby the smoothing-iron may be heated by a gas-jet from the 85 pipe in its interior, the pipe and its burner may be permanent fixtures, and yet the smoothing-iron may be vertically reciprocated without disturbing or moving said pipe, as and for the purpose specified.

3. The combination, with the table D, the ironing-board F, and means for supporting and reciprocating the same, of the vertical post L', fixed to the frame of the machine, the horizontal frame L, supported thereon, and having 90 vertical recesses in its arms, the vertical post Q', secured to frame L, the lever Q, pivoted in post Q', and means, substantially as specified, for operating the same, the hanger-frame P, attached to lever Q, the smoothing-irons O, the 95 bars N, connecting them, and the trunnions M on said bars journaled in the frame P and resting against the sides of said vertical recesses in frame L, as shown and described.

EDWARD WALKER.
